 Electronics, Cambridge, Mass., a corporation of
 Massachusetts

Filed Mar. 27, 1962, Ser. No. 182,899
 10 Claims. (Cl. 118—7)

The present invention relates to the deposition of thin films by evaporation at low pressure and, more particularly, to the monitoring and controlling of the rate of evaporation in such a system. Broadly such a system involves heating a selected source material to generate a stream of vapor, subjecting a particularly positioned substrate to the stream of vapor which condenses thereupon, and continuously evacuating the system in order to provide a free path for the stream of vapor. Evaporation rate is an important but difficult parameter to control in the production of thin films. Since evaporation rate is a strong function of source temperature, it cannot be effectively controlled by monitoring input power or source temperature.

The primary object of the present invention is to monitor the evaporation rate by a novel detection and control system in which part of the vapor stream is ionized. These ions are collected so as to provide an electrical signal and this electrical signal serves to control the heat applied to the source material. In a preferred system, the vapor stream is ionized by an electron beam and the source material is heated by an electron beam.

Other objects of the present invention will in part be obvious and will in part appear hereinafter.

The invention accordingly comprises the apparatus possessing the features, properties and relation of components that are exemplified in the following detailed disclosure, the scope of which will be indicated in the appended claims.

For a fuller understanding of the nature and objects of the present invention, reference should be had to the following detailed description, taken in connection with the accompanying drawing, which is a single figure in the form of a diagrammatic view, partly mechanical and partly electrical, of a preferred embodiment of the present invention.

Generally, the illustrated embodiment of the present invention includes an assembly having an evaporator section 10 and a detector section 12 disposed in a suitable evacuated chamber 14. Evaporator section 10 includes a crucible 16 for the reception of a source material. Crucible 16, which is electrically conducting, serves as an anode for the reception of electrons from an annular filament 18 serving as a cathode. The electron flow from filament 18 to crucible 16 heats crucible 16 and consequently causes a flow of vapor 20 from crucible 16 to a substrate 22 through detector section 12. Detector section includes two communicating ionization chambers 24 and 26. Chamber 26 is in the path of the vapor flow from crucible 16. Chamber 24 is outside the path of the vapor flow from crucible 16. A self-accelerated electron gun 27 directs an electron beam through chambers 24 and 26 in such a way as to ionize the vapor in chamber 24 and the vapor in chamber 26. Chambers 24 and 26 include ion collectors 28 and 30 respectively. The ion current from within chamber 26 to collector 30 is a function of evaporation rate and background gas pressure. The ion current from within chamber 24 to collector 28 is a function of background gas pressure only. The difference between the two ion currents is proportional to evaporation rate.

The ion current I_1 of chamber 26, which is composed of both residual gas ions and evaporating source material

2

ions, is related to the ionizing electron current I_0 as follows:

$$I_1 = I_0 (2 - e^{-N_v \sigma_v L_e} - e^{-N_B \sigma_B L_e})$$

where

N_v = No. of vapor molecules in chamber 26 per cu. cm.
 σ_v = Ionization cross-section of vapor in chamber 26 in cm^2 .

L_e = Path length of electrons through vapor

N_B = No. of vapor molecules in chamber 24 per cu. cm.

σ_B = Ionization cross-section of vapor in chamber 24 in cm^2 .

The ion current I_2 of chamber 24, which is composed of residual gas ions only, is similarly related to the ionizing electron current as follows:

$$I_2 = I_0 (1 - e^{-N_B \sigma_B L_e})$$

The difference between the two currents is proportional only to the vaporization rate thus,

$$I = I_1 - I_2 = I_0 (1 - e^{-N_v \sigma_v L_e})$$

since $e^{-N_v \sigma_v L_e}$ is very small, L_3 can be rewritten

$$I_3 = I_0 N_v \sigma_v L_e$$

but

$$N = P_v / K T_0$$

where:

P_v = vapor pressure

T_0 = crucible temperature, and

K = Boltzmann's constant

Therefore

$$I_3 = I_0 L_e \frac{\sigma_v}{K T_0} P_v$$

Since the temperature does not vary appreciably over wide ranges of P_v , $\sigma_v / K T_0$ can be considered a source material constant C_m and $I_0 L_e$ can be considered a system constant C_s so that

$$P_v = C_m C_s I_3$$

Since the evaporation rate W is a known function of P_v ,

$$W = f(L_3)$$

In the illustrated form of the assembly, crucible 16 and annular filament 18 are shown as being insulatedly mounted within an open ended conducting shield 32.

A power supply 34 generates between annular filament 18 and crucible 16 a voltage of the order of 3 kv. and a current of the order of 300 ma. The precise temperature of annular filament 18, the emission of which is temperature limited, is determined by a power supply 36 which adjustably delivers a voltage of the order of 10 v. and a current of the order of 10 a.

Chambers 24 and 26 are shown as being defined by conducting shields 38 and 40, which are insulatedly mounted within housing 14. Shields 38 and 40 are open ended along the axis of electron beam 42 from gun 27. Shield 40 provides a path for the flow of vapor from crucible 16. The electron beam path and the vapor flow path provided by shield 40 are at right angles to each other. Electron gun 27 includes an electron emitting filament 43 and a plurality of accelerating electrodes 44, 46 and 48. Filament 43 is heated by a power supply 50 which delivers a voltage of the order of 10 v. and a current of the order 10 a. The potential difference between filament 43 and the accelerating electrodes is established by a power supply 52 which delivers a voltage of the order of 400 v.

In operation, a high gain operational amplifier 53 is provided for amplifying an input signal that controls the power delivered to filament 18 by power supply 36. Operational amplifier 53 has a pair of inputs 54 and 56 which respectively are resistively coupled to collectors 28 and 30 of chambers 24 and 26. Error signals amplified by amplifier 52 are in reference to a preset voltage established

at 58. Thus, the ion current monitor will measure either input currents or the differential current depending on the mode of operation. The intensity of electron beam 42 is monitored by an operational amplifier 60 which applies a signal to power supply 50 in response to variations in the current from filament 43, a part of which is directed across a resistor 62. The opposed terminals of resistor 62 are applied to the inputs of operational amplifier 60 in order to produce error signals in reference to a present voltage at 64. The pressure within chamber 14 is reduced by a suitable vacuum pumping system 66 to a level below 10^{-3} mm. Hg.

The present invention thus provides a direct technique for precisely controlling and measuring evaporation rate in a vacuum deposition system. Since certain changes may be made in the above apparatus without departing from the scope of the invention herein involved, it is intended that all matter contained in the above description or shown in the accompanying drawing shall be interpreted in an illustrative and not in a limiting sense.

What is claimed:

1. A system comprising first means for heating a selected source material to generate a stream of vapor, second means for positioning a substrate in said stream, third means for continuously evacuating the region of said stream, fourth means for ionizing a proportion of said stream, fifth means for collecting ions therefrom in order to generate a signal and sixth means for applying said signal to said first means in order to control the temperature thereof.

2. The apparatus of claim 1 wherein said first means includes a crucible within which said source material may be held and a source of electrons between which and the crucible and electron flow may be established.

3. The apparatus of claim 1 wherein said fourth means provides a pair of chambers, seventh means for directing an electron beam through both of said chambers, one of said chambers being positioned in said vapor stream, and eighth means for comparing the ion currents generated within said chambers by said electron beam.

4. A system comprising first means for heating a selected source material to generate a stream of vapor, second means for positioning a substrate in said stream, third means for continuously evacuating the region of said stream, fourth means for ionizing a proportion of

45

said stream, fifth means for collecting ions therefrom in order to generate a signal, sixth means for applying said signal to said first means in order to control the temperature thereof, said first means includes a crucible within which said source material may be held and a source of electrons between which and said crucible an electron flow may be established, said sixth means controlling the intensity of said electron flow.

5. The apparatus of claim 4 wherein said fourth means provides a pair of chambers, seventh means for directing an electron beam through both of said chambers, one of said chambers being positioned in said vapor stream, and eighth means for comparing the ion currents generated within said chambers by said electron beam.

10 6. The apparatus of claim 5 wherein the ion and current in one of said chambers is perpendicular to said electron beam.

7. A system comprising a housing, a pump for evacuating said housing continuously, an electrically conducting crucible in said housing for reception of a material to be evaporated, a support in said housing for a substrate to be coated with said material when evaporated, said material when evaporated constituting a stream between said crucible and said substrate, a pair of electrical collectors partially bounding a pair of regions, an electron gun for directing an electron beam through said chambers, one of said chambers being disposed in said stream, the other of said chambers being spaced from said stream, an electron source for directing electrons to said crucible, and a system responsive to electrical currents from within said regions to said collectors in order to control the flow of electrons to said crucible.

20 8. The system of claim 7 wherein said system includes a differential amplifier having a pair of input terminals for the reception of signals from said pair of collectors.

9. The system of claim 7 wherein the flow of electrons to said crucible is established by an electric field between said crucible and said filament.

30 10. The system of claim 7 wherein said electron gun is self accelerated.
